UNITED STATES PATENT OFFICE

JOHN W. BESTLER, OF CHICAGO, ILLINOIS, ASSIGNOR TO THEO. A. KOCHS COMPANY, OF CHICAGO, ILLINOIS, A CORPORATION OF ILLINOIS

BRACKET FOR ELECTRIC CLIPPERS

Application filed December 26, 1928. Serial No. 328,452.

This invention which relates to brackets generally is designed particularly to support an electric clipper. For this purpose it is formed to fit into the slot or guide usually 5 provided at the top of the back of a barber's chair or the like for the reception of the head rest; and it combines in its structure a means for supporting an electric motor, and also for suspending the cutter head which is connected flexibly to the motor in a well known 10 manner. In order to serve most satisfactorily in the capacities noted, the bracket is specially formed in the peculiar manner which will hereinafter be explained.

15 A suggestive embodiment of my invention is set forth in the accompanying drawing in the manner following:

Figure 1 is a side elevation of the bracket as it appears when mounted operatively on 20 the back of a chair or seat, a clipper motor and cutter head being supported by the bracket in the intended manner;

Fig. 2 is a view in perspective of the bracket per se; and

25 Fig. 3 is a fragmentary detail showing the bracket end which provides support for the motor and cutter head.

In the drawing I have represented the back A of a seat or chair having in its upper 30 edge a slot or guideway for the reception of the usual head rest bar. The present bracket B which is in the form of a bar 4 is adapted to be fitted within the slot or guideway in the upper edge of the chair or seat back in 35 the manner illustrated in Fig. 1. The bar forming the bracket is bent upon itself at 5 to provide a depending portion 6 which lies adjacent the seat back along the rear side thereof; the bar is further bent laterally at 40 7 to project rearwardly and horizontally for an appreciable distance from the seat back, the bar end 8 being tapered or rounded, by preference, as shown.

A bar having the contour noted is pro- 45 vided further with an upstanding hook 9 at the extremity of its end 8. On the under side of the horizontal bar portion 7 is a shallow socket 10 adapted to receive one end 11 of a hook bolt C which may be made of round 50 wire bent into the general form of a rectan-

gle. The shank end of the hook bolt which is threaded at 12 is entered through an opening 13 in the horizontal portion of the bracket and in screw-threaded connection with a nut 14, which is rested upon the upper face 55 of this bracket portion. When the nut is tightened to the position shown in Fig. 3, the hook bolt is drawn tightly against the under side of this bracket portion so as to present a shoulder 15 in close engagement therewith. 60 In this position the hook end 11 is also held within the socket 10 so as to secure the hook against movement of every kind.

A bracket answering to the preceding description is particularly adapted to support 65 a clipper motor D having a bail 16 which may be secured within the hook C, as shown in Fig. 1. The motor shaft is in driving engagement with a flexible connection 17 leading to a cutter head E having an eye or 70 opening 18 for receiving the hook 9. The motor support, which is the hook C, becomes secure with tightening of the nut 14, but the cutter head may be removed from connection 75 with the hook 8 whenever it is to be placed in service. In such circumstances the motor is free to swing upon its mounting, according to the pull on the connection 17, and this is of advantage in the use of the instrument.

The present clipper bracket is advanta- 80 geous in that it is simple, compact, and easily applied to or removed from the back of a chair or seat. When so positioned it sustains the clipper motor in a central position 85 for convenient use of the cutter head, and no shift in the position of the motor is required in order that the cutter head may be placed wherever necessary for treatment of the person occupying the seat or chair.

I claim:

1. A portable supporting bracket for a bail supported motor from which is extended a flexible shaft, comprising a bar having one end adapted for reception within the head rest guideway of a chair back, said bar being 95 bent upon itself to provide a portion adapted to depend along the rear side of the chair back and having a horizontal portion which extends rearwardly therefrom, said horizontal portion being formed with a socket, and 100

an adjustable hooked bolt depending from said horizontal portion and presenting one end within the socket, and means for securing the other end of said bolt to said horizontal portion.

5 2. A portable motor and flexible shaft supporting and attaching means for barber chairs, comprising a bar-like bracket adapted for reception within the head rest guideway of a chair back, said bar being bent at one end to engage the rear side of the chair and provide a bracket arm, said arm having clamping means for detachably securing a motor adjacent the back of a chair, and means 10 projecting beyond said motor clamping means and adapted to engage and support a flexible shaft.

15 3. In a bracket of the kind described having a laterally extending arm terminating in an upwardly directed hook, and a socket adjacent the hook end, a second hook adjustably mounted in said bracket and having its free end normally engaging within said socket, and means for adjusting said second hook relative to said bracket and socket.

20 25 In testimony whereof I have hereunto set my hand this 22 day of December, 1928.

JOHN W. BESTLER.
